(57) **CLAIM**

The ornamental design for an ultrasonic diagnosis apparatus, as shown and described.

DESCRIPTION

FIG. 1 is a front view of a design for an ultrasonic diagnosis apparatus, as shown and described.

FIG. 2 is a back view of the ultrasonic diagnosis apparatus of FIG. 1.

FIG. 3 is a right side view of the ultrasonic diagnosis apparatus of FIG. 1.

FIG. 4 is a left side view of the ultrasonic diagnosis apparatus of FIG. 1.

FIG. 5 is a top view of the ultrasonic diagnosis apparatus of FIG. 1.

FIG. 6 is a bottom view of the ultrasonic diagnosis apparatus of FIG. 1.

FIG. 7 is a front perspective view of the ultrasonic diagnosis apparatus of FIG. 1; and,

FIG. 8 is a back perspective view of a design for the ultrasonic diagnosis apparatus of FIG. 1.

The broken lines show portions of the ultrasonic diagnosis apparatus that form no part of the claimed design.
